CASTING REEL FOR FISHING TACKLE

Rudolph W. Cantu, 2605 E. Rose, Orange, Calif.

Filed Nov. 8, 1960, Ser. No. 62,771

Term of patent 3½ years

(Cl. D31—4)

FIG. 1

The dominant features of my design reside in the portions shown in full lines. The side not shown is substantially the same as the side shown.

I claim:

The ornamental design for a casting reel for fishing tackle, substantially as shown and described.
